UNITED STATES PATENT OFFICE.

FAIRLEIGH S. DICKINSON, OF RUTHERFORD, NEW JERSEY.

VALVELESS SYRINGE.

1,307,245.

Specification of Letters Patent. Patented June 17, 1919.

Application filed February 20, 1919. Serial No. 278,137.

To all whom it may concern:

Be it known that I, FAIRLEIGH S. DICKINSON, a citizen of the United States, and a resident of Rutherford, in the county of Bergen and State of New Jersey, have invented a new and Improved Valveless Syringe, of which the following is a full, clear, and exact description.

The invention relates to syringes having a barrel and a compressible bulb for drawing a medicated liquid into the barrel and subsequently ejecting it therefrom to an afflicted part.

The object of the invention is to provide a new and improved valveless syringe arranged to permit the user to readily draw the liquid into the barrel and to prevent the liquid from passing into the rubber bulb on holding the syringe with its nozzle upward and with the liquid resting on the normally closed entrance to the bulb. Another object is to provide a valveless syringe which is exceedingly simple in construction and not liable to get easily out of order, at the same time permitting a quick and thorough sterilizing of the few parts forming the syringe.

With these and other objects in view the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a sectional side elevation of the valveless syringe with the nozzle end of the barrel shown in elevation and with the liquid drawn into the barrel;

Fig. 2 is a sectional side elevation of the same with the nozzle pointing upward;

Fig. 3 is an enlarged sectional plan view of the same on the line 3—3 of Fig. 2; and

Fig. 4 is an enlarged sectional elevation of the diaphragm showing the positions assumed by the latter on using the syringe.

The barrel 10 of the syringe is preferably made of glass and is provided at one end with a nozzle 11 and at the other end with a flaring mouth 12, and a rubber bulb 13 is used at this end of the barrel 10 and is provided with a neck 14 fitting snugly into the barrel and on to the flaring mouth 12, as plainly illustrated in Figs. 1 and 2. The neck 14 of the bulb 13 is provided with a

large opening 15 normally closed by a diaphragm 16 made of soft rubber or other suitable resilient material. The margin of the diaphragm 16 is vulcanized or otherwise attached to the edge of the neck 14 to practically form an integral part thereof. The diaphragm 16 is provided with, at least, one puncture, rupture or break 17, but, as shown in the drawings, a number of such punctures, ruptures or breaks are preferably formed in the diaphragm near the margin thereof but in register with the opening 15.

Normally the diaphragm 16 extends flat across the end of the neck 14 with the punctures, ruptures or breaks closed by the resiliency of the rubber of which the diaphragm is made. On using the syringe the operator first squeezes the rubber bulb 13 to compress the air contained in the bulb and thereby cause the compressed air to bulge the diaphragm 16 outward into the position shown at 16^a in Fig. 4 whereby the diaphragm is expanded and hence the punctures, ruptures or breaks 17 are opened to allow the air to pass into the barrel 10. The nozzle 11 is then immersed in a liquid after which the operator releases the bulb 13 to draw the liquid into the barrel 10 and to cause the diaphragm 16 to contract from the outwardly bulged and expanded position to normal position thereby closing the punctures, ruptures or breaks and then to move into inward bulging and expanded position, as indicated at 16^b in Fig. 4, to permit the air in the barrel to pass into the bulb 13 to reinflate the latter. When this has been done the diaphragm 16 by its resiliency returns to its normal flat contracted position whereby the punctures, ruptures or breaks 17 are again closed by the resiliency of the rubber of which the diaphragm is made. The operator can now turn the syringe upside down or into any inclined position without danger of the liquid flowing from the barrel into the bulb 13 as the neck 14 thereof is closed by the diaphragm 16.

By arranging the punctures, ruptures or breaks 17 near the margin of the diaphragm 16 the weight of the column of liquid resting on the diaphragm is not liable to open the punctures, ruptures or breaks and the column of liquid is partly sustained by the capillary attraction of the tube and partly by the diaphragm itself. The diaphragm is sufficiently strong to prevent the column of liquid from flexing it to such a degree as to

open the punctures 17 and hence no liquid is liable to pass into the bulb 13 when holding the barrel in upside down position, that is, with the nozzle upward as shown in 5 Fig. 2.

When it is desired to eject the liquid from the barrel 10 to the afflicted part then the operator squeezes the bulb 13 to compress the air therein. The compressed air acts 10 on the diaphragm 16 to bulge the same outward and thereby open the punctures, ruptures or breaks 17 as previously explained to allow the air under pressure to pass through the open punctures, ruptures or 15 breaks 17 into the barrel to eject the liquid therefrom to the afflicted part. As soon as the bulb 13 is relieved of pressure the diaphragm 16 immediately returns to normal flat position to prevent any liquid that may 20 remain in the barrel from passing into the bulb on holding the syringe upside down. Thus from the foregoing it will be seen that normally the barrel is disconnected from the interior of the bulb 13 and only on alternately pressing and releasing the bulb 13 25 communication is had between the interior of the bulb and the barrel for the exit and entrance of air as above explained.

It is expressly understood that the puncture, rupture or break in the diaphragm is diminutive and in making it none of the material of the diaphragm is removed and hence the resilient nature of the material readily closes the puncture and keeps the 35 same closed as long as the diaphragm remains in the normal flat position. The puncture, rupture or break is preferably made by piercing the rubber diaphragm with a suitable, sharply pointed instrument.

40 It is understood that in syringes having a rubber bulb, it is desirable that the medicated or other liquid does not pass into the bulb to avoid deterioration of the bulb by the influence of the medicated liquid. By 45 preventing the liquid from passing into the bulb the user of the syringe can at all times see whether the medicated liquid contained in the barrel is in proper condition or not.

The improvement is shown applied to 50 syringe barrels but it may be applied to the suction bulb of a breast pump or similar apparatus to prevent the milk drawn from the breast to pass into the bulb. It will also be noticed that by the use of the 55 bulb with a punctured diaphragm in a breast

pump the suction action is retarded and hence the milk is slowly drawn from the breast thus preventing undue pain.

Having thus described my invention, I claim as new and desire to secure by Letters Patent:—

1. A syringe, comprising a barrel provided at one end with a discharge nozzle, a compressible bulb having a neck fitting the other end of the said barrel and a diaphragm 65 of resilient material, the said diaphragm located between the liquid-receiving portion of the barrel and the bulb, the diaphragm being provided with at least one puncture normally closed by the action of 70 the resilient material of which the diaphragm is made, the diaphragm expanding on application of pressure on either side of the diaphragm to open the puncture to allow air to pass from the bulb into the barrel or 75 vice versa, the diaphragm on the release of pressure returning to normal contracted position thereby closing the puncture.

2. A valveless syringe, comprising a barrel provided at one end with a discharge nozzle 80 and at the other end with a flaring mouth, a compressible bulb having a neck fitting within the said flaring mouth and a diaphragm secured to the said neck and formed of resilient material, the diaphragm 85 having at least one diminutive puncture normally closed by the action of the resilient material of which the diaphragm is made, the diaphragm on pressing the bulb and compressing the air causing the latter to bulge 90 the diaphragm outwardly and thereby expanding the diaphragm and opening the puncture to allow escape of the air contained in the bulb into the barrel, the diaphragm, on relieving the pressure on the 95 bulb with the nozzle inserted in a liquid returning first to normal contracted position to close the puncture and then bulging inward to again open the puncture to draw the liquid into the barrel and to allow the air 100 in the latter to pass by way of the open puncture into the bulb to reinflate the latter, the diaphragm after reinflation of the bulb returning to normal flat position thereby closing the puncture to prevent the liquid 105 from passing into the bulb on holding the syringe with the nozzle upward and with the liquid resting on the diaphragm.

FAIRLEIGH S. DICKINSON.
